UNITED STATES PATENT OFFICE.

JESSE M. GARRETT, OF ST. LOUIS, MISSOURI.

BURNER.

Application filed July 10, 1922. Serial No. 573,898.

To all whom it may concern:

Be it known that I, JESSE M. GARRETT, a citizen of the United States, residing at St. Louis, in the county of St. Louis and State of Missouri, have invented new and useful Improvements in Burners, of which the following is a specification.

My present invention has reference to a liquid fuel burner for generating steam in boilers or for heating stoves, furnaces or the like.

My object is to produce a burner in which the liquid fuel is mixed with steam and forcibly ejected from the burner so that the same will be scattered around all parts of the fire box.

A further object is to produce a liquid fuel burner in which the fuel and steam are first conducted to a mixing chamber and find an outlet through apertures therein and thereafter contact with the blades of a turbine to revolve the latter and to direct the mixed fuel against a baffle plate by which it is directed against all parts of the fire box so that an even flame will be obtained in the entire surface of the fire box and all flues connected therewith will be evenly heated.

The foregoing, and other objects which will present themselves as the nature of the invention is better understood, may be accomplished by a construction, combination and operative association of parts, such as is disclosed by the drawings which accompany and which form part of this application.

In the drawings:—

Figure 1 is a view of a fire box which is partly broken away illustrating the application of the improvement therein.

Figure 2 is a sectional view on the line 2—2 of Figure 1, on an enlarged scale.

Figure 3 is a horizontal sectional view on the line 3—3 of Figure 2.

Figure 4 is a similar sectional view on the line 4—4 of Figure 2.

The remaining figures illustrate details.

Referring now to the drawings in detail, F indicates a fire box for a boiler, furnace, stove or the like. Arranged in the fire box is a burner constructed in accordance with this invention.

The burner includes an upper and what I will term a body portion 1 that constitutes a plurality of parts which essentially include a mixing chamber that has a rotatable member in the nature of a turbine thereabove.

The mixing chamber is indicated by the numeral 3, the same having its upper portion in the nature of a tubular member provided with exterior threads 2 and 3 and a partition 4. This partition is provided with any desired number of circumferentially arranged preferably small openings 5. The lower portion of the chamber 2 is rounded inwardly, being substantially cone-shaped and terminating in a reduced neck 6 which is interiorly threaded. Screwed in the neck is a pipe 7, the pipe extending through the bottom of the fire box. The pipe 7 is in the nature of a conductor for the oil or other liquid fuel. The pipe 7 has a branch 8 through which the fuel enters. The pipe 7 may have its bottom closed in which event the same is provided with an opening for a jet pipe 9 through which steam under pressure is conducted.

Screwed on the threaded end 3 of the mixing chamber 2 there is a sleeve 10. The sleeve 10 is provided at its upper end with an inwardly directed flange 11. The inner periphery of the flange 11 is round and the under face thereof is provided with a continuous rounded concavity 12. The upper edge of the mixing chamber 2 is provided with a rounded depression 13, the purpose of which arrangement will be presently described.

There is preferably threaded on the mixing chamber a locking nut 12' whereby the distance between the concaved shoulders 12 and 13 may be regulated.

The revoluble element which I have termed the turbine is broadly indicated by the numeral 14. This element includes a ring-like periphery 15 that is approximately centrally formed with an outstanding flange 16, the flange being round in plan and the opposed faces of the said flange being concaved. Between the concaved upper face of the flange 16 and the concaved inner face 12 of the flange 11 there are anti-frictional balls 17, and between the concaved lower face of the flange 16 and the concavity in the upper end of the mixing chamber there are similar anti-frictional balls 18. In this manner the member 14 may be freely rotated. The member 14 is centrally formed with a tubular portion 19 which is interiorly threaded, and between the tube 19 and the ring 15 there are angularly arranged blades 20.

Screwed in the tube 19 there is a short

pipe 21. The pipe 21 is, of course, exteriorly threaded, and arranged thereon there is a saucer-shaped baffle member 22, the same having its open face directed away from the burner 1. Screwed on the pipe and in contact with the inner wall of the baffle 22 is a nut 23. Screwed on the pipe 21 and in contact with the lower face of the baffle 22 there is a nut 24. The nuts 23 and 24 hold the cup-shaped baffle member properly adjusted with respect to the turbine 14.

The operation of the device may be briefly described as follows:—

Steam and oil or other liquid fuel are let in the mixing chamber through the pipe 7. This mixture escapes through the apertures 5 in the partition 4 in a thoroughly mixed condition. The mixture contacts with the blades 20 of the turbine and revolving the same becomes thoroughly broken so that the mixture is really vaporized (after the fire has been started), when the same is delivered into the fire box F. The blades of the turbine tend to spread the fuel upwardly and outwardly with respect to the burner, while the baffle 23 directs the fuel laterally of the burner in all directions so that every part of the fire box will receive fuel and as this fuel is ignited, all parts of the fire box will be heated. A certain quantity of the fuel will pass through the rather restricted passage in the pipe 21, and this fuel when ignited will be delivered in a straight line toward the top of the fire box.

It is believed that the foregoing description, when taken in connection with the drawings will fully set forth the construction and advantages of the improvement to those skilled in the art to which such inventions relate, but it is to be understood that I am not to be restricted to the illustrated embodiment herein set forth, but may make such changes therefrom which may later suggest themselves, as fall within the scope of what I claim.

Having described the invention, I claim:

1. In a liquid burner, a mixing chamber, a turbine therein, a baffle thereabove, means for delivering a liquid fuel separately through the baffle and against the blades of the turbine to revolve the turbine to cause the latter to direct the fuel against the

baffle and to be scattered by contact therewith.

2. In a liquid fuel burner, a mixing chamber having an apertured partition therein, a turbine having angularly arranged blades journaled above the partition, a baffle above the turbine, means for admitting a liquid fuel under pressure through the apertured partition against the blades of the turbine for revolving the turbine and caused to exert a whirling action against the fuel to force the same outward of the mixing chamber against the baffle, and by virtue of contact therewith to be scattered therefrom.

3. In a liquid fuel burner, a mixing chamber having an apertured partition therein, a turbine having angle blades thereabove, anti-frictional bearings between the mixing chamber and the turbine, a pipe member connected to and extending centrally from the turbine, a baffle member adjustable on the pipe member, and means for directing a liquid fuel under pressure through the apertures of the partition to cause said fuel to contact with the blades of the turbine to revolve the latter and by virtue thereof to direct the fuel in a whirling spray outward of the mixing chamber and against the baffle member, and certain of the fuel admitted to the mixing chamber being directed through the pipe into the baffle member.

4. In a liquid fuel burner, a mixing chamber having an apertured partition therein and a lower reduced end, a liquid fuel conducting pipe connected to the reduced end of the chamber, a steam jet in the pipe below the fuel inlet thereof, a flanged sleeve adjustable on the burner, a turbine having an outer ring portion provided with a flange, anti-frictional bearings between this flange, the flange of the sleeve and the upper edge of the mixing chamber, means between the sleeve and the mixing chamber for adjusting the anti-frictional bearings, a pipe member arranged centrally in the turbine and projecting thereabove, a saucer-shaped baffle member adjustable on the pipe, and angle blades between the ring and pipe of the turbine, all as and for the purpose set forth.

In testimony whereof I affix my signature.
JESSE M. GARRETT.
